(57) **CLAIM**

The ornamental design for an electrical power grommet for a worksurface, as shown and described.

DESCRIPTION

FIG. 1 is a top perspective view of a first embodiment of an electrical power grommet for a worksurface of our new design;

FIG. 2 is another top perspective view thereof;

FIG. 3 is a bottom perspective view thereof;

FIG. 4 is another bottom perspective view thereof;

FIG. 5 is a front elevation thereof;

FIG. 6 is a rear elevation thereof;

FIG. 7 is a right side elevation thereof;

FIG. 8 is a left side elevation thereof;

FIG. 9 is a top plan view thereof;

FIG. 10 is a bottom plan view thereof;

FIG. 11 is a top perspective view of a second embodiment of an electrical power grommet for a worksurface of our new design;

FIG. 12 is another top perspective view thereof;

FIG. 13 is a bottom perspective view thereof;

FIG. 14 is another bottom perspective view thereof;

FIG. 15 is a front elevation thereof;

FIG. 16 is a rear elevation thereof;

FIG. 17 is a right side elevation thereof;

FIG. 18 is a left side elevation thereof;

FIG. 19 is a top plan view thereof;

FIG. 20 is a bottom plan view thereof;

FIG. 21 is a top perspective view of a third embodiment of an electrical power grommet for a worksurface of our new design;

FIG. 22 is another top perspective view thereof;

FIG. 23 is a bottom perspective view thereof;

FIG. 24 is another bottom perspective view thereof;

FIG. 25 is a front elevation thereof;

FIG. 26 is a rear elevation thereof;

FIG. 27 is a right side elevation thereof;

FIG. 28 is a left side elevation thereof;

FIG. 29 is a top plan view thereof; and,

FIG. 30 is a bottom plan view thereof.

The broken lines in the drawings are for the purpose of illustrating portions of the electrical power grommet for a worksurface that form no part of the claimed design.
